[57] CLAIM

The ornamental design for a sports equipment cart, as shown and described.

DESCRIPTION

FIG. 1 is a front perspective view of a sports equipment cart showing my new design;

FIG. 2 is a top plan view thereof;

FIG. 3 is a side elevational view thereof, the opposite side being identical thereto;

FIG. 4 is a front elevational view thereof;

FIG. 5 is a rear elevational view thereof;

FIG. 6 is a bottom plan view thereof;

FIG. 7 is a side elevational view of a sports equipment cart showing a second embodiment of my new design, the only differences being in the wheels and legs;

FIG. 8 is a front elevational view of FIG. 7; and

FIG. 9 is a bottom plan view of FIG. 7.
